UNITED STATES PATENT OFFICE.

GEORGE M. EATON, OF PITTSBURGH, PENNSYLVANIA, ASSIGNOR TO WESTINGHOUSE ELECTRIC & MANUFACTURING COMPANY, A CORPORATION OF PENNSYLVANIA.

TRANSFORMER TANK.

Application filed January 14, 1921. Serial No. 437,161.

To all whom it may concern:

Be it known that I, GEORGE M. EATON, a citizen of the United States, and a resident of Pittsburgh, in the county of Allegheny and State of Pennsylvania, have invented a new and useful Improvement in Transformer Tanks, of which the following is a specification.

My invention relates to heat-dissipating devices and it has particular relation to devices of the above indicated character wherein electrical or other apparatus is immersed within a cooling fluid.

More specifically, my invention relates to transformer tanks, the sides of which are provided with air-cooled corrugations or radiators.

One of the objects of my invention is to provide a device of the character described in which the walls of the tank comprise a plurality of separately formed corrugated members secured together in substantially side-by-side relation and communicating with the interior of the tank at the upper and lower portions thereof.

Another object of my invention is to provide a device of the character described, the separate elements of which are constructed of pressed sheet metal and of such form as to be quickly and easily assembled and which reinforce and strengthen the entire structure.

Another object of my invention is to provide a heat-dissipating device in which the walls of the individual radiator units are disposed at angles to each other, thus not only strengthening the units but forming a weld or thin passage or duct within which the cooling medium may freely circulate.

Heretofore, in devices of this general character, it has been customary to construct a tank having radiator units which communicate with the tank for the entire lengths of the units. In such structures, it has been observed that there is a tendency for the oil or other cooling medium contained within the radiator to become substantially static or to circulate very slowly therein, thus materially reducing the rate of heat dissipation.

In accordance with my invention, I construct radiator units with a plurality of separate and complementary elements so formed that, when assembled in side-by-side relation, the outer edges and central por-

tions of the inner edges thereof abut to form a duct or passageway therebetween. The passages thus formed communicate with the tank at the upper and lower extremities thereof and constitute the separate and individual channels through which the oil or other cooling medium may circulate.

Referring to the drawings, Figure 1 is a plan view of a transformer tank constructed in accordance with my invention.

Fig. 2 is a view, partly in elevation and partly in vertical longitudinal section, on line II—II of Fig. 1.

Fig. 3 is an edge view of one of the complementary members of a radiating unit, as viewed in the direction indicated by the arrows III in Fig. 1 and in which one of the side walls of the member is of substantially dish-shape and the other wall relatively flat.

Fig. 4 is a side elevational view of the member illustrated in Fig. 3 taken in the direction indicated by line IV—IV in Fig. 1.

Fig. 5 is an edge view of a modified form of my invention in which each of the side walls of the U-shaped member is depressed.

Fig. 6 is a side elevation of the structure shown in Fig. 5.

Referring to the drawings, a transformer tank, comprising a side wall 1 and a top and a bottom, 2 and 3, respectively, is provided with a plurality of radially extending radiator units 4 arranged with the inner extremities thereof in abutting relation to constitute the wall 1 of the tank.

Each of the units 4 comprises a plurality of complementary members 5 of substantially U-shape. One of the walls 6 of the member 5 is formed with a depression 7 which extends practically the entire length of the same and with a flange 8 which extends around the outer edge thereof. The other wall 9 of the member 5 is substantially flat and is adapted to engage the depressed portion of the adjacent member 5 to form a radiating unit.

The wall 6 is also provided, along the inner edge thereof, with a raised portion 10 which is adapted to be engaged by the relatively flat wall 9 to prevent communication between the radiator unit thus formed and the interior of the tank, except at the upper and lower portions thereof. The walls 6 and 9 of each of the units 4 incline outwardly from each other, as best shown in

Fig. 1 and form a well defined passage for the cooling medium.

The members 5 may be formed with each side thereof provided with depressions 11, 5 as indicated in Figs. 5 and 6. By means of this construction, the members 5 which constitute the sides of adjacent units, are disposed at angles to each other. That is to say, the side walls of each of the units 10 formed by the legs of the elements 5 diverge outwardly from each other.

It will be apparent that by means of the construction described above, a transformer tank may be constructed of a plurality of 15 radiating units which communicate with the interior of the tank at the upper and lower extremities thereof, thus causing the circulation of a cooling medium within the respective units.

20 I claim as my invention:

1. A heat-dissipating device comprising a tank and radiator units, the central portions of said units having substantially triangular cross-sectional areas and the end 25 portions thereof having substantially rectangular cross-sectional areas.

2. A heat-dissipating device comprising a receptacle adapted to contain a heating or 30 cooling medium, and a plurality of radiator units communicating with said receptacle, the side walls of each unit being disposed at an angle to each other and co-operating with the walls of the adjacent units to form the wall of said tank.

35 3. A transformer tank comprising a plurality of radiator units, the inner extremities thereof arranged to form the wall of said tank, said units being formed of a plurality of complementary members and the 40 intermediate portions of said members being in contact with each other and the end

portions thereof being spaced from each other to provide communication with said tank at the upper and lower portions thereof.

45

4. A transformer tank comprising a plurality of radiator units, said units being formed of a plurality of complementary members of substantially U-shape adapted to be arranged in substantially side-by-side relation, the central portions of the inner edges of said members being in engagement with each other to form the wall of said tank, said units being in communication with said tank at the upper and lower portions only thereof.

50

5. A transformer tank comprising a plurality of radiator units, said units being formed of a plurality of complementary members of substantially U-shape, one of the legs of said unit being depressed and the other leg thereof being substantially flat and adapted to be arranged in substantially side-by-side relation, with the flat portion of said member in engagement with the depressed portion of the next adjacent member, said depressed portion of said unit communicating with said tank at the upper and lower portions thereof.

55

6. A transformer tank comprising a plurality of radiator units, said units severally comprising a plurality of complementary elements, said elements constituting the sides of adjacent units and having raised portions adjacent the inner edges thereof to close 70 said units with respect to said tank along the central portions thereof.

60

In testimony whereof, I have hereunto 75 subscribed my name this 29th day of December, 1920.

GEORGE M. EATON.
